UNITED STATES PATENT OFFICE.

JOSEPH R. SHORE, OF NEWARK, NEW JERSEY, ASSIGNOR TO AMERICAN CONCRETE
STEEL COMPANY, OF NEWARK, NEW JERSEY.

SCAFFOLDING FOR CENTERING AND THE LIKE.

Application filed April 23, 1921. Serial No. 463,880.

To all whom it may concern:

Be it known that I, JOSEPH R. SHORE, a citizen of the United States, and a resident of Newark, county of Essex, and State of New Jersey, have invented certain new and useful Improvements in Scaffolding for Centering and the like, of which the following is a specification.

This invention relates to an improved support or scaffold for temporary use, such as is employed for supporting centering of concrete structures, but, of course, being adapted for use with tile or other materials necessarily supported while setting or being otherwise secured in place.

The advantages of the structure are that it requires much less lumber than is used in the old form of centering support, that less labor and time are used in erecting and removing it, that it insures greater working space below, that it permits a greater number of re-uses, and that it is very substantial for use under super-imposed loads.

The invention includes a series of girders and beams which are each a unitary structure and so constructed as to withstand the required load, done by providing trusses on girders and beams so as to give the required rigidity and to provide a plain top surface, these being supported on suitable uprights.

The invention is illustrated in the accompanying drawings, in which Figure 1 is a perspective view, broken away to show a scaffolding made according to my improved invention, illustrating different methods of arranging the timbers. Figure 2 is a side view of one end of a girder or beam, and Figure 3 is a similar view of a modified form of construction. Figure 4 is a perspective view showing a beam in section and illustrating one form of strut. Figure 5 is a face view of the bottom of a modified form of strut, and Figure 6 is a perspective view showing some of the parts in section and illustrating the arrangement of the parts adjacent to a column.

The old method of erecting scaffolding for centering and like purposes has been to arrange a large number of uprights, which are suitably cross-braced and to which horizontal beams are nailed or otherwise secured, and then the boards for forming the centering to support a cement, tile or similar ceiling or floor placed on top of these. The old form necessitated a large number of up-

rights in heavy structures, so close together, in fact, as to provide but little working space underneath, this being confined usually to aisles or longitudinal spaces between rows of uprights.

When the work had been completed and the whole structure had to be taken out, in the old form in the knocking down of the scaffolding a great deal of lumber was destroyed, which is a considerable factor because so much lumber is used in the structure itself. With this large number of uprights, especially on ground floors, they had been placed close together, which, of course, makes it necessary to put some of them on the ground and not on the cement footings of the structure, and in cold weather, where it is necessary to place braziers or fires to keep the cement from freezing, the thawing that takes place underneath many of the uprights permits them to settle into the ground, and the centering consequently settles, and there is an uneven surface at the top of the scaffolding, due to this settling.

In my improved scaffolding the uprights are placed much further apart, in most cases it being possible to use on the bottom or ground floor the cement footings of the columns and bridge the spaces between the uprights by beams, which in themselves are unitary structures and are laid on the uprights, and then, if necessary, in turn are used as girders to support transverse beams bridging the spaces between the girders, and there is but little nailing to be done, and when the device is to be knocked down and removed there is very little spoiling or destroying of lumber, and there is much less lumber and labor used in the erection, removing and re-erection than with the old form of scaffolding.

The main vertical support of the scaffold is usually in the form of uprights 10, it being usual to employ joists or studding commensurate in size with the load to be carried, and suitably braced by boards 11 which are usually nailed to the uprights and around the place where the concrete columns are to rise. Extending from one upright to the other I place girders 12, as will be seen from Figure 1, these girders being usually in the form of beams which are trussed, having the struts 13 and tension rods 14 which bear on the bottom part of the struts and extend to the ends of the beams or girders 12, being

usually provided with turn-buckles 15 by means of which they can be given the proper tension, and by means of which any shrinkage in the beam or other looseness due to 5 other causes can be taken up.

I prefer to leave a top surface that is devoid of projections and is substantially flat. For this reason I chamfer the ends of the 10 beams or girders and pass the tension rods

- 10 through said chamfered ends and provide them, on their outer ends, with nuts 16 bearing against the bearing plates 17, as will be seen more particularly from Figures 2 and 3. In the case of girders I usually provide
- 15 double tension rods 14, in this case the bearing plates 17 being replaced by plates 18 which project beyond the side edges of the girder and through which projecting ends the tension rods pass and are secured.

- 20 Spanning the space between the girders I arrange the beams 19, which are trussed similar to the manner in which the girders are trussed, in the shorter type using only one strut placed in the middle of the beam 25 and having the tension rod bearing on the under side of this strut, as will be seen from Figure 3.

Figure 4 shows a detail of a strut, this strut having a channel 20 at the top into 30 which the girder or beam sets, thus preventing lateral motion of the two parts relative to each other, and the foot 21 is recessed to receive the tension rod 14.

In Figure 5 I show a wooden strut 22 which 35 is provided with a foot 23 channelled to receive the bottom end of the strut and having its lower part perforated to receive the tension rod or tension rods 14. It will thus be seen that each beam or girder is a unitary 40 structure in itself, and as a trussed element it is simply laid in its proper place in the scaffolding, is placed in position without the necessity of nailing it and is consequently easy to remove, and they are not bulky, so 45 that many of them can be transported in a motor truck or the like.

On the top of the beams I place the cen-

tering, usually consisting of boards 24 which form a surface on which the concrete, tile or other platform, such as a ceiling or under 50 surface of a floor, can be supported until it sets and is able to maintain itself in position.

In Figure 1 I show also the cooperation 55 of this form of scaffolding with the forms used around columns, these columns being shown in dotted outline at 25, and the surrounding timbers to maintain the scaffold are shown in the immediate foreground in Figure 1, this portion of the framework be- 60 ing of the usual type.

If desired, I may provide the uprights with broader tops as by providing each with a bracket 26, shown in Figure 2, or a cap 27, shown to the left in Figure 1, which is ex- 65 tensive enough to permit the setting of the ends of four beams on the top of one up- right.

I claim:

1. A scaffolding for supporting centering 70 comprising uprights, readily removable trussed girders of non-collapsible form sup- ported on the tops of the uprights, and read- ily removable trussed beams of non-collaps- 75 ible form supported at their ends on the girders, said structure permitting the plac- 80 ing of the uprights only on the footings of columns, and centering arranged on said beams to hold a cement floor thereon and to prevent said cement from contacting with the beams or girders.

2. A scaffolding for centering comprising a substantially rectangular framework of trussed girders, a set of trussed beams sup- 85 ported at their ends on the girders, and up- 90 rights arranged only at the ends of the girders and supporting the same, whereby the uprights can be located on the footings of columns, and whereby the intermediate space between uprights can be left clear. 90

In testimony that I claim the foregoing, I have hereto set my hand, this 22nd day of April, 1921.

JOSEPH R. SHORE.
